ROTARY SPRAY ARM FOR A CLEANING MACHINE

George J. Federighi and Tore H. Noren,
San Francisco, Calif.

Application March 14, 1958, Serial No. 721,546

7 Claims. (Cl. 239—183)

The present invention relates to improvements in a rotary spray arm for a cleaning machine. It consists of the combinations, constructions and arrangement of parts, as hereinafter described and claimed:

In commercial dishwashing machines, the rotary arms in the washing compartment receive wash water from a pump, which draws its water from a reservoir placed at the bottom of the compartment. It is the general practice to provide a strainer for covering the top of the reservoir; but, in spite of this strainer, olive pits, toothpicks and food particles pass therethrough and are drawn by the pump into the water that is forced into the rotary spray arms. This foreign matter clogs the outlet nozzles of the spray arms and makes them inefficient. The rotary spray arms usually are not turned by mechanical means, but rather the nozzles direct the issuing water at angles so as to cause the arms to revolve. It is quite apparent that when the arms and nozzles become clogged with foreign matter, the arms will cease to rotate.

The conventional rotary spray arms are usually formed from a unitary casting; and, if the nozzles become clogged, it is necessary to remove the arms from the machine for cleaning them.

As the cardinal object of our invention, we provide a rotary spray arm for a cleaning machine, which has covers provided over access openings formed in the spray arm bodies, whereby access may be had to the liquid passageways for cleaning purposes. Also, when the covers are removed, the interiors of the nozzles may be cleaned. The cleaning operation may be accomplished without removing the spray arm from the machine. Although the rotary spray arm is designed primarily for use in dishwashing machines, it may be used in other types of cleaning machines, wherein a liquid is projected against articles to be cleaned.

As further object of our invention is to provide a rotary spray arm of the type described, in which the covers may be readily removed and then replaced, without requiring the use of tools. The attaching means for the covers make use of centrifugal force, resulting from the rotation of the spray arm about an axis, for urging the covers into liquid-tight relation with the spray arm bodies.

Other objects and advantages will appear as the specification proceeds. The novel features will be set forth in the claims hereunto appended.

Drawings

For a better understanding of our invention, reference should be had to the accompanying drawings, forming part of this specification, in which:

Figure 1 is a top plan view of our rotary spray arm for a cleaning machine;

Figure 2 is a side elevational view thereof, with parts being shown in section to illustrate the mounting mechanism for the spray arm;

Figure 3 is a view similar to Figure 1, but with the covers removed;

2

Figure 4 is an enlarged transverse sectional view taken along the line IV—IV of Figure 2;

Figure 5 is an enlarged top plan view of the left-hand portion of Figure 1; and

Figure 6 is a longitudinal sectional view taken along the irregular line VI—VI of Figure 5.

Although we have shown only the preferred form of our invention, it should be understood that various changes, or modifications, may be made within the scope of the annexed claims without departing from the spirit thereof.

Detailed description

In carrying our invention into practice, we provide a rotary spray arm indicated generally at A, which defines a pair of spray arm bodies B that extend non-radially from a central hub portion C. The spray arm bodies are identical with one another and are formed integral with each other.

Each spray arm body B is made hollow so as to define a liquid-conveying passageway D extending longitudinally thereof. Referring to Figures 2, 5 and 6, it will be noted that the central hub portion C has a vertical hub sleeve 10 connected thereto by a plurality of spider arms 11 and gussets 12. Moreover, an elbow fitting E (see Figure 2) has a rim 14 that projects upwardly into a central opening 15 fashioned in the lower part of the spray arm bodies B. Also, a boss 16 is provided on the interior of the elbow fitting E into which a vertical journal shaft 17 is threaded, as at 18. The journal shaft coincides with the vertical axis F about which the spray arm A is rotated. The shaft 17 projects upwardly in the hub sleeve 10, with a bushing 19 being interposed therebetween. Thus the spray arm A is mounted for rotation about the axis F and is supported by the shaft 17.

The central hub portion C is provided with an upstanding circular flange 20 over which a cap 21 is placed, this cap being secured to the shaft 17 by a cap bolt 22 (see Figure 2). As shown, a washer 23 is interposed between the cap 21 and the top of the hub sleeve 10.

The incoming water for the rotary spray arm A is delivered through the inlet passageway 24 of the elbow fitting E by means of a pump (not shown). This water flows under pressure through the passageway D of each of the spray arm bodies B, as suggested by the arrows 25 in Figure 6 of the drawings. The pump draws its water from a reservoir (not shown) in the conventional manner.

As shown in Figures 2, 3 and 6, each of the spray arm bodies B is fashioned with a longitudinal opening 26 at its top, which gives access to the passageway D for cleaning purposes. The top surface 27 of the spray arm bodies B is planed so as to be perfectly flat. A pair of covers G are removably secured to the spray arm bodies B and enclose the openings 26. Each cover G is fashioned with a plurality of spray nozzles 28, each nozzle having at least one outlet opening 29 for liquid. The spray nozzle openings 29 communicate through the openings 26 in the spray arm bodies with the passageways D, whereby liquid flowing through the passageways D may be discharged through the nozzles 28.

In Figures 1 and 5, we show certain openings 29a in the outermost spray nozzles 28, which openings are inclined relative to the vertical. As liquid is discharged through these particular openings, under pressure, the spray arm A will be caused to turn in the direction of the arrows 30 due to the reaction of the liquid as it leaves the nozzles.

Each spray arm body B has an outer end provided with a hook 31 that projects toward the axis of rotation F, as clearly shown in Figures 1, 2, 3, 5 and 6 of the drawings. The outer end of each cover G is provided with a locking tongue 32, which is disposed to engage under-

neath the hook 31 adjacent thereto for securing the outer end of the cover G to the spray arm body B over which the particular cover is applied. As an important feature, the covers G are slideable along the flat top surfaces 27 of the spray arm bodies B so that the covers G will be urged by centrifugal force toward the hooks 31 as the spray arm bodies are turned about the axis F.

At the outer ends of each of the spray arm bodies B, the locking tongue 32 thereon is provided with a pair of spaced-apart projections 33 (see Figure 5). These projections are disposed to straddle the hook 31 associated therewith and to contact the hook to position the outer end of the cover G with respect to the spray arm body B and for preventing lateral movement of the tongue 32 with respect to the hook 31. In Figure 6, it will be observed that the tongue and the hook have tapered upper and lower surfaces, respectively. These surfaces are complimentary and taper in directions to wedge the cover G against the spray arm body B, when the cover is urged outwardly relative to the spray arm body by centrifugal force, as the spray arm A is rotated about the axis F.

A pair of spring-loaded keepers H engage with the inner end portions of the covers G to removably anchor these ends of the covers to the spray arm bodies B. As shown in Figures 1, 5 and 6, the inner end of each cover G is fashioned with a key-hole slot J therein. Each slot defines an enlarged portion 34 having a restricted portion 35 extending therefrom toward the axis F (see Figure 5). A pair of indexing bolts K are anchored to the tops of the spray arm bodies B, each having a head 36 dimensioned to pass through the enlarged portion 34 of one of the slots J, when a cover G is being applied to or removed from a spray arm body B. Moreover, each bolt has a shank 37 dimensioned to enter the restricted portion 35 of the key-hole slot J, when the cover G is moved outwardly along the spray arm body B.

With particular reference to Figure 6, it will be noted that a keeper H has been shown as having a washer-shaped head 38, the latter being positioned to abut an upper surface 39 of the cover, when the shank 37 is disposed in the restricted portion 35 of the key-hole slot J. A compression spring 40 encircles the shank 37 of each bolt and bears against the head 36 of the bolt and the washer-shaped head 38 of the keeper to yieldingly urge the latter against the upper surface 39 of the cover. Each bolt K is threaded into a threaded bore 41 in the spray arm body B (see Figure 6) for up and down adjustment of the bolt. The keeper H is provided with a sleeve 42 that surrounds the shank 37 of the bolt K and projects downwardly from the washer-shaped head 38 of the keeper H to protect exposed threads 43 on the bolt against damage, when the cover G is being applied to the spray arm body B or removed therefrom. Both of the indexing bolts K and the spring-pressed keepers are identical with one another.

Summary

Assuming that the rotary spray arm A is mounted on the journal shaft 17 in the manner shown in Figure 2, the covers G may be readily applied to the spray arm bodies B as follows:

The cover G is advanced downwardly against the top surface 27 of one of the spray arm bodies B, with the head 36 of the indexing bolt K passing upwardly through the enlarged portion 34 of one of the key-hole slots J, until the cover G comes to rest on the arm body B. At this time, the spaced-apart projections 33 at the outer end of the cover G should be positioned so that they will straddle the hook 31, when the cover G is moved outwardly along the surface 27. As the locking tongue 32 passes under the hook 31, the tapering surfaces of the tongue and hook will urge the outer end of the cover G into liquid-tight relation with the top sur-

face 27 of the spray arm body B. During this outward sliding movement of the cover G, the sleeve 42 on the spring-loaded keeper H will pass into the restricted portion 35 of the key-hole slot J. The spring 40 will press down on the washer-shaped head 38 of the keeper, thus urging the inner end of the cover down against the upper surface 27 of the spray arm body B. The other cover G may be applied in a like manner. Both covers will then enclose the longitudinal openings 26 of the spray arm bodies.

When the liquid is forced through the inlet elbow fitting E, it will flow into the passageways D, and will issue through the openings 29 and 29a, causing the spray arm A to rotate in the direction of the arrows 30 (see Figure 1).

As previously pointed out, the passageways D and the nozzles 28 often become clogged, such as by olive pits and food particles. The covers G may be readily removed, thus giving access to the passageways and the interior of the nozzles 28 for cleaning purposes. No tools are required for this purpose and the spray arm A need not be removed from the journal shaft 17.

The various parts may be made of any suitable material to prevent corrosion, and we do not wish to be limited in this respect.

We claim:

1. In a rotary spray arm for a cleaning machine: a spray arm body mounted for rotation about an axis; the spray arm body having a liquid-conveying passageway extending longitudinally thereof; the spray arm body being fashioned with a longitudinal opening giving access to the passageway for cleaning purposes; the spray arm body having an outer end provided with a hook projecting toward said axis; a removable cover disposed to enclose the opening, and having an outer end provided with a locking tongue, which is disposed to engage underneath the hook to secure the outer end of the cover to the spray arm body; the cover being slideable along the spray arm body so that the cover will be urged by centrifugal force toward the hook as the spray arm body is rotated about said axis; the cover having an inner end; and means removably securing the inner end of the cover to the spray arm body; the cover being fashioned with spray nozzles, which communicate through the opening in the spray arm body with the passageway, whereby liquid flowing through the passageway may be discharged through the nozzles.

2. The rotary spray arm for a cleaning machine, as defined in claim 1; and in which the tongue is provided with a pair of spaced-apart projections, which are disposed to straddle the hook and contact therewith to position the outer end of the cover with respect to the spray arm body and for preventing lateral movement of the tongue with respect to the hook.

3. The rotary spray arm for a cleaning machine, as defined in claim 2; and in which the tongue and the hook have tapered upper and lower surfaces, respectively; these surfaces being complimentary and tapering in directions to wedge the cover against the spray arm body, when the cover is urged outwardly relative to the spray arm body by said centrifugal force.

4. In a rotary spray arm for a cleaning machine: a spray arm body mounted for rotation about an axis; the spray arm body having a liquid-conveying passageway extending longitudinally thereof; the spray arm body being fashioned with a longitudinal opening giving access to the passageway for cleaning purposes; the spray arm body having an outer end provided with a hook projecting toward said axis; a removable cover disposed to enclose the opening, and having an outer end provided with a locking tongue, which is disposed to engage underneath the hook to secure the outer end of the cover to the spray arm body; the cover being slideable along the spray arm body so that the cover will be urged by centrifugal force toward the hook as the spray arm body is rotated

about said axis; the cover having an inner end; and a spring-loaded keeper engaging with an inner end portion of the cover to removably anchor this end of the cover to the spray arm body; the cover being fashioned with spray nozzles, which communicate through the opening in the spray arm body with the passageway, whereby liquid flowing through the passageway may be discharged through the nozzles.

5. In a rotary spray arm for a cleaning machine: a spray arm body mounted for rotation about an axis; the spray arm body having a liquid-conveying passageway extending longitudinally thereof; the spray arm body being fashioned with a longitudinal opening giving access to the passageway for cleaning purposes; the spray arm body having an outer end provided with a hook projecting toward said axis; a removable cover disposed to enclose the opening, and having an outer end provided with a locking tongue, which is disposed to engage underneath the hook to secure the outer end of the cover to the spray arm body; the cover being slidable along the spray arm body so that the cover will be urged by centrifugal force toward the hook as the spray arm body is rotated about said axis; the cover having an inner end; the inner end of the cover being fashioned with a key-hole slot therein; said slot defining an enlarged portion having a restricted portion extending therefrom toward said axis; an indexing bolt anchored to the spray arm body, and having a head dimensioned for passing through the enlarged portion of the slot, when the cover is being applied to or removed from the spray arm body; the bolt having a shank dimensioned to enter the restricted portion of the slot, when the cover is moved outwardly along the spray arm body; a keeper mounted on the shank of the bolt, and having a washer-shaped head positioned to abut an upper surface of the cover, when the shank is disposed in the restricted portion of the slot; and a spring encircling the shank and bearing against the head of the bolt and the washer-shaped head of the keeper to yieldingly urge the latter against the upper surface of the cover; the cover being fashioned with spray nozzles, which communicate through the opening in the spray arm body with the passageway, whereby liquid flowing

through the passageway may be discharged through the nozzles.

5. The rotary spray arm for a cleaning machine, as defined in claim 5; and in which the bolt is threaded into the spray arm body for up and down adjustment therein; the keeper being provided with a sleeve surrounding the shank of the bolt and projecting downwardly from the washer-shaped head of the keeper to protect exposed threads on the bolt against damage, when the cover is being applied to the spray arm body or removed therefrom.

7. In a rotary spray arm for a cleaning machine: a spray arm body mounted for rotation about an axis; the spray arm body having a liquid-conveying passageway extending longitudinally thereof; the spray arm body being fashioned with a longitudinal opening giving access to the passageway for cleaning purposes; the spray arm body having an outer end provided with a hook projecting toward said axis; a removable cover disposed to enclose the opening, and having an outer end provided with a locking tongue, which is disposed to engage underneath the hook to secure the outer end of the cover to the spray arm body; the cover being slidable along the spray arm body so that the cover will be urged by centrifugal force toward the hook as the spray arm body is rotated about said axis; the cover being fashioned with spray nozzles, which communicate through the opening in the spray arm body with the passageway, whereby liquid flowing through the passageway may be discharged through the nozzles; the nozzles having interiors that are exposed for cleaning purposes, when the cover is removed from the spray arm body; and means removably securing the inner end of the cover to the spray arm body.
